UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed June 1, 1920. Serial No. 385,650.

My invention relates to mining apparatus. It has for its object to provide an improved mining apparatus especially adapted to the transport and unloading and loading of a mining machine. A further object of my invention is to provide an improved mining machine truck having improved and simplified mechanism for maintaining the mining machine in transport position, driving the truck therefrom, supplying current to the mining machine, and loading and unloading the mining machine in different relations to the truck. These and other advantages of my improved construction will, however, hereinafter more fully appear.

While my invention may be embodied in various forms, I have shown for purposes of illustration in the accompanying drawings one embodiment which the same may assume in practice.

In these drawings,—

Fig. 1 is a plan view of a mining machine truck constructed in accordance with this form of improvement, the front end of the truck being broken away.

Fig. 2 is a side elevation of the same, the mining machine being shown in dotted lines in transport position thereon.

Fig. 3 is a transverse sectional view on line 3—3 of Figures 1 and 2.

Fig. 4 is a longitudinal sectional view on line 4—4 of Fig. 3.

Fig. 5 is a side elevation showing the apparatus in position for unloading, the mining machine being shown after its initial longitudinal movement.

Fig. 6 is a side elevation showing the mining machine after its tilting movement.

Fig. 7 is a plan view showing the position of the parts when unloading at an angle.

Fig. 8 is a side elevation showing the apparatus in position for loading, the mining machine being shown in a plurality of positions.

Fig. 9 is a side elevation showing the mining machine in a different position during loading.

Fig. 10 is a plan view showing the position of the parts during loading from an angle.

Fig. 11 is a detail view of the latch mechanism.

In this illustrative construction I have

shown a wheeled truck frame 1 carried on a plurality of wheels 2 adapted to run over a mine track 3 and to transport a mining machine 4 of suitable construction, herein of a standard room-and-pillar type and provided with a flexible feed member 5 adapted to be actuated by a feed operating member 6 driven by the machine motor, and also having a gear 7 on its rear end likewise driven from the motor and adapted to mesh with a cooperating gear 8 carried on the rear end of the truck and connected through improved means hereinafter described, to rotate a sprocket 9 driving a chain 10 connected to the truck wheels.

In my improved construction, the upper surface of the front of the frame 1 is disposed in a plane adjacent the tops of the wheels 2 and has a rotatable horizontally disposed plate 11, slightly wider than the frame, mounted on its front extremity on a vertical swivel 12. As shown this swivel 12 is located in the longitudinal center line of the truck and slightly in rear of the transverse center line of the plate 11 and of the front truck axle. Further, this plate is preferably also rotatably supported on a series of rollers 13 carried by the lower frame and rotatable on horizontal axes and disposed in longitudinal and transverse lines through the swivel and with the forward roller a greater distance from the swivel. Carried upon this plate 11 and having its rear end suitably supported in the frame 1 is an elongated longitudinally flanged machine receiving and guiding member or frame 14 having suitable transversely connected tie plates 15 and open front and rear ends, the former as usually preferable being flared as shown. This frame 14 is in turn pivoted on a transverse axis between the ends thereof, at 16, to forwardly disposed extensions 17, herein in the form of angle irons, carried on the opposite sides of the front end of the plate 11, suitable removable pivot pins preferably being seated in the flanges on the member 14 and on the extensions 17 at points in advance of the front truck wheels. As shown, this member 14 is also preferably provided at its front end with nose portions 18 adapted to engage the bottom and hold up the front end of the member 14 when the latter is depressed as

shown in Fig. 6. Upon this member 14 and between the same and the mining machine 4, is also preferably provided a pan 19 open at its opposite ends and provided with flanged sides. This pan normally acts as a support for the mining machine when the latter is in transport position, and is unloaded with the mining machine over the member 14 during the unloading operation 10 and carried to the face, where it acts as a sumping pan during the sumping operation. After the machine has been sumped into the coal, and before the same is again loaded upon the truck this pan 19 is also placed in 15 the position shown in Fig. 8, with one end upon the depressed end of the member 14, and the other on the bottom, the same being so disposed as to act as a guide for the mining machine during the loading operation 20 hereinafter described and reduce the angle between the truck and the bottom. Thus it will be noted that this pan 19 performs a dual function, the same acting as a sumping and loading pan at different 25 times and during transport being carried beneath the machine upon the member 14. As shown, this pan 19 is also provided on each side with a plurality of lugs 20, 21, adapted successively to cooperate with a latch 22 on 30 the rear end of the mining machine, the parts cooperating during loading and unloading as hereinafter described.

Disposed at the rear end of the truck is the truck driving mechanism including the gear 8 driven by the mining machine gear 7 and driving the sprocket 9 and chain connection 10 for the truck wheels. As shown, the gear 8 is connected, as by a screw 23, to the reduced upper end 24 of an upright 35 worm shaft 25 journaled in suitable removable side roller bearings 26 and end thrust bearings 27, in the housing frame 28 carried on the truck. As shown, this gear is also provided with an elongated hub keyed 40 to the reduced portion 24 by a key 29, and is bodily removable to permit access to the bearings 26 upon removal of the screw 23. The thrust bearings 27 are herein also similarly held in position by a pinned washer 30 and an axial screw 31 removably attached 45 to the lower end of the shaft, a removable cap 32 cooperating in seating the bearing, and with the washer 30 and screw 31 being removable to permit access to the bearings. 50 Here, attention is also directed to the fact that by removing the cap 32 and screw 31, the entire shaft 25 with its upper gear and bearings may be lifted out of the housing. Formed upon the shaft 25 at a point intermediate its ends, is also a worm 33 which in 55 turn meshes with a worm gear 34 enclosed in the housing 28 and preferably running in oil therein, suitable oil plugs 35 and 36 being provided for filling and 60 draining the housing. The worm gear

34 is, as shown, preferably removably connected, as by screws or bolts 37, to a hub 38, in turn fixed to a sleeve 39 rotatable on a plurality of reduced portions 40 and 41 formed on the end of a transverse wheel 70 driving shaft 42, journaled in the housing. As shown this sleeve 39 is also rotatably mounted in the housing, one end of the same being enclosed in suitable ball bearings 43 carried in a suitable recessed member 44 on 75 the frame. The sleeve 39 is also connected to a reduced portion 45 on the end of the shaft by removably connected sectional end bearing members 46 which also retain the ball bearings in place. As illustrated, a cap 80 47 also fits into the recessed member 44 in such a manner as to assist in holding the ball bearings in position and is attached to the outside of the housing by screws 48, the construction being such that, upon the removal 85 of this member 47 and the end bearing members 46, the ball bearings 43 may be bodily withdrawn from the housing when desired, while upon removal of the members 47, 46, and the members 78, 64, 65, with the side 90 frame plate through which the member 78 extends, the shaft 42 with the friction thereon may be bodily withdrawn in the opposite direction. As shown, suitable bearing sleeves 95 49 and 50 are provided between the sleeve and the reduced portions 40 and 41 of the shaft and the sleeve is also provided with a collar 51 on its right hand end which cooperates with the bearing members 46 to hold the sleeve 39 securely in place. This 100 sleeve 39 is also operatively connected to a suitable clutch, the same herein being rigidly connected as by a key 52 with a sleeve on an outer clutch member 53 disposed coaxially with the shaft and adapted to cooperate 105 with an inner coaxially arranged expandable clutch member 54 pivotally connected by toggle links 55 with a clutch shipper 56 movable longitudinally on the shaft 42 relative to a spider 57 keyed to the shaft at 58 and held against longitudinal movement relative to the shaft by a collar 59 formed on the shaft. Cooperating with the rotatable shipper 56 is a longitudinally movable cooperating shipper member 60 mounted on a 110 reduced portion of the member 56. As shown, a ball bearing 61 is provided between this member 60 and the member 53 and a collar 62 is fixed to the member 56 at the opposite end of the member 60, the construction being such that the member 60 may be moved longitudinally to move the member 56 longitudinally but the member 60 will not rotate with the member 56. As shown 115 in dotted lines in Fig. 3, the member 60 is also provided with lugs 63 engageable with a pivoted shipper lever 64 pivoted on the housing at 65, beneath the shaft 42, and having its upper end adjustably pivoted at 66 to a transversely disposed toggle rod 67 120

125 68 to 130

which is in turn pivotally connected at 68 to a point intermediate the ends of a transversely disposed handle lever 69 pivoted at one end at 70 to the top of the housing. 5 Herein, this lever 69 also has pivoted to it at 68 a depending bell crank or member 71 having a handle portion 72 adapted to be gripped by an operator grasping the handle 69, and a lower extension 73 normally adapted 10 to engage an abutment 74 formed on the casing and prevent an unintentional maximum loading of the friction clutch. As shown, the shaft 42 also carries on one of its ends a sleeved truck wheel sprocket 9 15 keyed to the shaft at 75 and removably held in position thereon by a screw 76, the sprocket herein also being journaled on the frame in suitable roller bearings 77 and located in an enclosing member 78 extending over the 20 sprocket in such a manner as to protect the operator from entanglement with a chain connected to the sprocket. This sprocket 9 is in turn also connected through a chain 10 with a suitable cooperating sprocket 79 carried 25 on a truck axle, herein the rear axle 80, which is itself connected through a chain and sprocket connection 81 with the front axle 82 of the truck.

Operatively connected to the motor, herein 30 through the clutch mechanism just described, is my improved reeling mechanism. As shown, the constantly rotatable member 53 of the clutch is grooved on its outer periphery as at 83 to receive a 35 belt 84 extending rearwardly therefrom and around a corresponding pulley 85 formed at one end of a suitable cable reel 86 journaled on the rear end of the truck in suitable supports and having a cable 87 wound thereon 40 and guided in its movement toward or from the reel by suitable cable guides 88 at the rear end of the truck. As shown, the cable 87 is also electrically connected through connector plugs 89 and branched conductors 90 45 passing over an improved conductor spacing and supporting housed frame 91, with the motor of the mining machine carried on the truck. It will also be observed that on one side of frame 91 is carried a hook 92 50 adapted to cooperate with the hub of a normally operative belt tensioning idler 93 pivotally mounted on the rear end of a rearwardly extending arm 94, the construction being such that the idler may be held out 55 of contact with the belt 84 whenever desired. By this construction, it will be observed that the reel 86 may be driven while the truck is stationary by simply first throwing down the idler 93 in such a manner as to place the 60 proper tension upon the belt 84, and then starting the mining machine motor.

Operatively associated with the machine and the truck are also improved cooperating means for holding the machine in proper 65 position upon the truck. One of these

means is shown to comprise a transversely disposed angle iron 95 mounted upon the rear end of the pan 19 and disposed in the loaded position of the parts, just beneath the truck driving gear 7. As shown, this 70 angle iron 95 is provided with a sloping surface adapted to slidably engage and underlie a cooperating upwardly extending lip 96 formed on the gear housing, the construction being such that the machine in its rearward movement on the truck is thus guided in such a manner as to bring its gear 7 into proper mesh with the gear 8 and to hold these gears in the desired mesh during 75 transport regardless of the irregularities of the track. It will also be noted that a longitudinally disposed lever 97 is pivoted in the truck upon a transverse pivot 98 above the shaft 42 and pivotally connected through toggle 99 with a machine holding finger 100 80 adapted to be received in a suitable aperture 101 in the rear end of the machine, to hold the latter rigidly in position upon the truck, the construction being such that by pulling the rear end of the lever 97 upward the 85 finger 100 will be readily withdrawn from the aperture 101. Attention is also directed to the fact that at each side of the truck frame, means are provided to prevent the 90 frame 12 from swinging about its several pivots 12 and 16 when the machine is on the truck. These means herein comprise pivotally mounted hooks 102 fixed to a transversely disposed rock shaft 103 in turn operated by an operating handle 104 at one end 95 of the shaft. These members 102 are thus movable by that handle relative to the truck body in such a manner as to cause the members 102, when in their upright position, to engage pins 102' on the frame and thereby 100 inhibit lateral and tilting movement of the frame 14 about its pivots, the members 102 also being movable about the axis of the rock shaft 103 into their inoperative position 105 illustrated in dotted lines in Fig. 2 wherein they do not interfere with a movement of the frame 14 about either of its pivots.

To further control the truck, it will also be noted that a suitable truck brake 105 is provided, the same herein acting upon one 110 of the axles of the truck and being provided with a suitably connected operating lever or handle 106 located adjacent the lever 69. Attention is also directed to the fact that alongside the truck and on the same side as the levers 69, 104 and 106, a platform 107 is provided preferably having thereon a higher platform or tool box 108 adapted 115 to form a seat upon which the operator may ride and be in a convenient position relative to the several control members. It will also be noted that a usual abutment 109 is provided on the rear end of the truck, herein in the form of a chain fork, to receive during 120 loading the rear end of the flexible 125

member of the mining machine, which member herein assumes the form of a chain 5. To cooperate with the chain during loading, the usual hooks 110 are also provided on the front end of the frame 14. To further cooperate with this chain, it will, moreover, be noted that in my improved construction, longitudinally disposed laterally spaced notches 111 are provided in the rear edge 13 of the rear plate 15 of the frame 14 to receive the feed chain when threaded for right or left hand cutting. To support the rear end of the truck during unloading or loading, a suitable support 112 is also preferably provided.

In considering the operation of my improved construction, we will first consider the transporting and unloading operations, referring more particularly to Figures 2, 20 5, 6 and 7. When the machine is to be moved about the mine, the same is locked on its truck in the position indicated in Fig. 2 and transported under its own power to the place desired, the machine motor driving the 25 truck wheels through the gears 7, 8, the friction clutch 53, 54, the shaft 42, and the chain and sprocket connection 9, 10, etc. When it is desired to unload the machine, the truck driving clutch is disconnected 30 through the lever 69, the brake 10 is set through the lever 106, the support 112 set, and the finger 100 is released through the lever 97. Then the flexible feed chain 5 is connected between the feed operating member 35 6 of the machine and the hooks 110, or, if desired, directly to a point adjacent the face, and the machine motor is started, whereupon the entire machine 4 is fed along its feed chain and relative to the truck 40 carrying with its pan 19 due to the engagement of the latch 22 with the cooperating rear lug 20 on the pan. As the machine moves outward over the frame 14, the latter will be tilted from the horizontal position 45 shown in Figures 1 and 2 to the tilted position illustrated in Figure 6, the machine and pan then moving down the frame 14 until the machine is supported on the bottom. The pan 19, it will be noted, remains connected to the machine due to the engagement of the latch 22 with the lug 20 so that thus a summing frame is provided beneath the machine adapted to guide the same relative to the face during the summing 50 operation, the latch 22 being successively released from the lugs 20 and 21 as the machine moves into the face. After the machine has been summed into the coal, the pan 19 is then returned to the position illustrated 55 in Figure 8 wherein it forms a continuation of the still tilted frame 14 and cooperates therewith to reduce the loading angle, the parts then being ready to receive the machine when the latter has completed its cut.

60 65 When this occurs, the feed chain may be con-

nected directly to the chain fork 109, but it is usually connected to a jack 113 as by chain lines shown in Fig. 8 and operatively connected between the bottom and the roof at a point within the open end of the pan 14 and in rear of the rear of the pan 19. Thus, by drawing in its chain, the machine may be fed up on to the pan 19. Thereafter, the jack 113 is removed and the end of the feed chain is connected in one of the notches 111 on the rear end of the frame 14, as shown in the upper dotted chain position in Fig. 8, i. e. in such a manner that the machine may move up the inclined frame 14. During this movement, the latch 22 is permitted to engage the front lug 21 on the pan 19 in such a manner as to cause the pan 19 to move with the machine up the inclined frame 14. After the machine has moved sufficiently far on the frame 14 to over-balance the latter into horizontal position (Fig. 9), the end of the feed chain is then removed from the notch 111 and connected to the chain fork 109, as shown in the dotted line in Fig. 9, and the latch 22 is raised to permit it to pass freely over the lug 21, the machine then moving relative to the pan 19 and rearwardly to bring its gear 7 into mesh with the gear 8 on the truck, the rearward movement of the machine being limited and directed by the cooperating guiding and holding means 95 and 96. When in this position, the members 100 and 102 are operated, and the machine then being securely re-locked in position upon the truck, is ready for 100 transport.

When it is desired to unload the machine at an angle relative to the truck or track, it will be observed that the entire frame 14 may be manually swiveled relative to the truck as soon as the machine is released for lateral movement by lowering the members 102. Preferably, however, the same is caused to be swiveled by the chain automatically by simply laying the chain along the front end of the truck and connecting its advance end of one side of the truck at the place desired. Obviously, with the frame so disposed, the machine may be unloaded therefrom (Fig. 7) substantially as previously described. Also the truck may be loaded in the same general manner (Fig. 10) likewise previously described. However, in returning the machine to the truck, it will be observed that when the machine has tilted the frame 14 into horizontal position and before the machine has been moved to the rear end of that frame the feed chain is preferably released from its notch 111 and connected to the chain fork 109 in such a manner as, while the machine moves rearward to complete its movement relative to the frame 14, to swing that frame automatically on its swivel and into alignment with the truck. The chain is preferably also con-

nected directly to the chain fork 109 instead of to a notch 111, the sliding engagement of the chain with the side of the frame 14, then serving to swing the frame and machine 5 as the machine moves. Thus, it will be observed that the machine is automatically loaded and swung into position with only two hitches of the feed chain.

As a result of my improvement, it will be 10 observed that an improved mechanism of the swivel type is produced whereby the machine may nevertheless be moved directly longitudinally off the truck whenever desired without intermediate angular movements, thereby expediting the discharge of the machine from the truck. It will further be evident that through the use of the sumping pan carried on the truck and movable 15 with the machine, the latter is rendered ready for sumping as soon as unloaded on the bottom, thereby avoiding the necessity for setting additional gear. Through the use of this sumping pan in the loading operation, it will also be evident that the angle 20 between the bottom and the tilting frame is reduced in such a manner that the loading operation is materially expedited. Through the provision of my improved connecting means for the feed chain, it will also be observed 25 that the operations of unloading and loading at an angle are facilitated and speeded up, the automatic swinging movement of the machine eliminating the necessity for manual effort and delays in re-connecting the chain. Through my improved 30 reeling mechanism, it is also made possible not only to wind in or feed out the cable as the machine moves relative to the track, but also to wind up the cable when the machine 35 is at a standstill, thereby enabling the transport movement of the machine to be expedited through reducing the delays heretofore necessary when moving between the points in the entry where the cable is connected to the line. Attention is also directed 40 to the exceedingly rugged and simple character of the several mechanisms cooperating to form the truck and reel drive and to the improved means provided herein for preventing unintentional maximum loading of 45 the friction clutch and consequent damage to the parts. These and other advantages of my improved construction will be apparent to those skilled in the art.

50 While I have in this application specifically described one embodiment which my invention may assume in practice, it will be understood that this is used for purposes of illustration and that the invention may be modified and embodied in various forms 55 without departing from its spirit or the scope of the appended claims.

What I claim as new and desire to secure by Letters Patent is:

60 1. In a mining apparatus, a rigid wheeled

truck frame, a rigid machine receiving member thereon tiltably and horizontally swiveled at points substantially midway between its ends and on the front of said frame, truck wheel driving mechanism including a member rotatable by a mining machine on said receiving member, and a feed member abutment carried by the rear end of said frame. 70

2. In a mining apparatus, a rigid wheeled truck frame, a rigid machine receiving member thereon tiltably and horizontally swiveled at points substantially midway between its ends and on the front of said frame, truck wheel driving mechanism including a member rotatable by a mining machine on 80 said receiving member, and feed member abutments carried by the rear ends of said frame and receiving member. 75

3. In a mining apparatus, a rigid wheeled truck frame, a rigid machine receiving member thereon overlying the wheels thereof and tiltably and horizontally swiveled on the front end of said frame, and truck wheel driving and conductor reeling mechanism on the rear end of said frame including a driving member adapted to mesh with a part on a mining machine on said receiving member and a friction clutch having a clutch drum forming a reel driving element and a cooperating relatively adjustable wheel driving 90 element. 85

4. In a mining apparatus, a truck, a member swiveled on the front end thereof on a vertical axis, roller mechanism operatively connected between said elements on opposite 100 sides and in front and rear of said swivel, the front roller mechanism being disposed a greater distance from the latter than the others, and a machine receiving member carried on said member adapted to slidably receive a unitary mining machine. 105

5. In a mining apparatus, a truck, a member swiveled on the front end thereof on a vertical axis, roller mechanism between said member and truck disposed on opposite sides 110 and in front and rear of said swivel, the front roller mechanism being at a greater distance from said swivel than the others and a machine receiving frame tiltably mounted on said member on an axis substantially in 115 alinement with said front roller mechanism.

6. In a mining apparatus, a wheeled truck, a machine receiving frame including a member overlying and swiveled for horizontal movement on the front end of said 120 truck, truck driving mechanism on said truck including an element adapted to be driven by a moving element on a mining machine on said frame, and means operable independently of a mining machine for holding 125 said frame in alinement with said truck and first mentioned element, and for preventing any substantial vertical movement of said frame. 130

7. In a mining apparatus, a truck, a ma-

chine receiving frame including a plate overlying and swiveled for horizontal movement on the front end thereof, truck driving mechanism on said truck including an element adapted to mesh with a moving element on a mining machine on said frame, and means operable independently of a mining machine for holding said frame in alinement with said truck and first mentioned element substantially in a predetermined vertical spaced relation.

8. In a mining apparatus, a wheeled truck, a vertically tilttable machine receiving frame including an operatively connected plate overlying and swiveled for horizontal movement on the front end of said truck, truck driving mechanism on said truck including an element adapted to be driven by a moving element of a mining machine on said frame, and means supplemental to said mechanism for maintaining said frame in transport position including mechanism for holding it in alinement and mechanism for preventing tilting thereof.

9. In a mining apparatus, a wheeled truck, a vertically tilttable machine receiving frame including an operatively connected plate overlying and swiveled for horizontal movement on the front end of said truck, truck driving mechanism on said truck including an element adapted to be driven by a moving element of a mining machine on said frame, and means supplemental to said mechanism for maintaining said frame in transport position including a single mechanism for inhibiting lateral swinging or vertical tilting thereof.

10. In a mining apparatus, a truck, a machine receiving frame swiveled for horizontal movement thereon, truck driving mechanism on said truck including an element adapted to be driven by a moving element of a mining machine on said frame, and means including a plurality of operatively connected and simultaneously movable members for holding said frame in alinement with said truck and first mentioned element.

11. In a mining apparatus, a truck, a machine receiving frame swiveled for horizontal movement thereon, truck driving mechanism on said truck including an element adapted to be driven by a moving element of a mining machine on said frame, and means including a plurality of movable members and a single operating member therefor for holding said frame in alinement with said truck and first mentioned element.

12. In a mining apparatus, a truck, a machine receiving frame swiveled for horizontal movement thereon, truck driving mechanism including an element adapted to be driven by a moving element of a mining machine on said frame, and means including a plurality of operatively connected and simultaneously operable swinging members on

opposite sides of said truck for holding said frame in a predetermined alinement with said first mentioned element.

13. In a mining apparatus, a truck, a machine receiving frame swiveled for horizontal movement thereon, truck driving mechanism including an element on said truck adapted to be driven by a moving element of a mining machine on said frame, and means for holding said frame in alinement with said first mentioned element including a plurality of operatively connected simultaneously swinging members on opposite sides of said truck and an adjusting member at one side of said truck.

14. In a mining apparatus, a truck adapted to receive a mining machine, a holding member on said truck engageable with a mining machine on said truck, and toggle mechanism controlling said member.

15. In a mining apparatus, a truck adapted to receive a mining machine, a hook on said truck engageable with a mining machine thereon, a hook operating member pivoted on said truck, and means forming a toggle connection connected to said operating member and to said hook.

16. In a mining apparatus, a truck presenting tilttable machine guiding means, a mining machine thereon having a flexible feeding member and truck driving means, and means independent of said flexible member and truck driving means automatically operative upon longitudinal movement of said machine relative to said guiding means to prevent vertical movement of the latter.

17. In a mining apparatus, a truck, a tilttable mining machine receiving member thereon, a mining machine thereon having a flexible feeding member and truck driving means, and means independent of said flexible member and truck driving means automatically operative upon longitudinal movement of said mining machine on said member for preventing tilting movement of the latter.

18. In a mining apparatus, a truck having truck driving means adapted to be driven by a moving part of a mining machine, a swiveled machine receiving member on said truck, a mining machine on said receiving member having a flexible feeding member, and means independent of said truck driving means and said flexible feeding member for automatically inhibiting swiveling movement in one direction of said receiving member when said machine is moved into a predetermined relation to said truck driving means.

19. In a mining apparatus, a truck having truck driving means adapted to be driven by a moving part of a mining machine, a tilttable machine receiving member on said truck, a mining machine movable

on said receiving member having a flexible feeding member, and means independent of said truck driving means and said flexible feeding member for automatically inhibiting 5 tilting movement of said receiving member when said machine is moved into a predetermined relation to said truck driving means.

20. In a mining apparatus, a truck, a tilt-
able machine guiding member thereon, truck
driving mechanism including a member
driven by a moving part of a machine on
said guiding member, and automatically
operative means independent of a mining
15 machine on said guiding member for pre-
venting vertical movement of said guiding
member relative to said truck driving
member.

21. In a mining apparatus, a truck pre-
senting tilttable machine guiding means, a
mining machine movable longitudinally
thereof and having truck driving mecha-
nism, and means separate from said mecha-
nism including a lip carried on the rear
25 end of said truck engageable upon longi-
tudinal movement of said machine to pre-
vent vertical movement thereof.

22. In a mining apparatus, a truck, a
tiltable machine guiding member thereon,
30 and means including interengaging lips car-
ried on the rear end of said truck and guid-
ing member engageable upon longitudinal
movement of the latter relative to said truck
to prevent vertical movement of said guid-
35 ing member.

23. In a mining apparatus, a truck, a
horizontally movable swiveled member, a
40 machine receiving frame tilttable about a
horizontal axis thereon, a machine guiding
member movable on said tilttable member,
and connections operative independently of
a machine for preventing tilting movement
45 operatively connected between said guiding
member and said truck.

24. In a mining apparatus, a truck, a
horizontally movable swiveled member, a
50 machine receiving frame tilttable about a
horizontal axis thereon, a machine guiding
member movable on said tilttable member,
and operative connections between said re-
ceiving frame and truck for preventing
55 swiveling of the former operable independ-
ently of a machine.

25. In a mining apparatus, a wheeled min-
ing machine receiving truck, truck wheel
driving mechanism thereon including a
single truck movement controlling friction
clutch on said truck having an element ro-
60 tatable while the truck is at rest and a co-
operating element, a cable reel on said truck,
and a driving connection between said reel
and a part supported and rotated by said
rotatable element independently of said co-
65 operating element.

26. In a mining apparatus, a wheeled truck

frame, truck driving mechanism thereon in-
cluding a clutch having an external rotating
clutch element, a cable reel on said truck,
and a flexible driving connection between
said reel and external element in radial aline-
70 ment with the latter.

27. In a mining apparatus, a wheeled min-
ing machine receiving truck, truck wheel
driving mechanism thereon including a ro-
tatable clutch element, a reel carried by said
75 truck, and a flexible connection therefor
directly connected to said clutch element.

28. In a mining apparatus, a wheeled min-
ing machine receiving truck, truck wheel
driving mechanism thereon including a 80
friction clutch having a clutch element rotat-
able while the truck is at rest, a cable reel
on said truck, and a driving connection to
said reel directly connected to said clutch
element. 85

29. In a mining apparatus, a wheeled min-
ing machine receiving truck, truck wheel
driving mechanism thereon including a
clutch having a clutch element rotatable
while the truck is at rest, a cable reel carried
90 by said truck, and driving means therefor
including a driving element supported by
said clutch element.

30. In a mining apparatus, a wheeled truck,
truck driving mechanism, a cable reel
carried by said truck and rotatable on an axis
fixed relative to said driving mechanism, a
flexible connection between said driving
mechanism and said reel, and means for
automatically tensioning said connection. 95

31. In a mining apparatus, a wheeled truck,
truck driving mechanism, a cable reel
carried by said truck and rotatable on an axis
fixed relative to said driving mechanism,
a flexible connection between said driving
105 mechanism and said reel, means for auto-
matically tensioning said connection, and
means for controlling the tension at the will
of the operator to vary the speed of said
reel. 110

32. In a mining apparatus, a wheeled truck,
truck driving mechanism therefor in-
cluding a clutch, shipper mechanism therefor
disposed on one side of said clutch, a cable
reel carried by said truck, and flexible driv-
115 ing connections between said truck driving
mechanism and reel and leading from said
mechanism at a point between the shipper
mechanism and the other side of said clutch.

33. In a mining apparatus, a wheeled truck,
driving mechanism therefor including
a clutch and shaft associated therewith,
spaced supporting bearings for said shaft, a
reel carried by said truck, and means dis-
120 posed between said bearings adapted to
receive a flexible connection leading to said
reel. 125

34. In a mining apparatus, a wheeled truck,
truck driving mechanism therefor in-
cluding a shaft, a driven gear and clutch
130

mechanism thereon, shipper mechanism for said clutch, a cable reel carried by said truck, and means disposed between said gear and shipper mechanism adapted to receive a flexible driving connection leading to said reel.

35. In a mining apparatus, a wheeled truck, truck driving mechanism therefor including a shaft, a driven gear and clutch mechanism thereon, shipper mechanism for said clutch, a cable reel carried by said truck, and means disposed between said gear and shipper mechanism adapted to receive a flexible driving connection leading to said reel and adapted to be continuously operative while said truck is standing still.

36. In a mining apparatus, a wheeled truck carrying a cable reel, truck driving mechanism therefor including a driven shaft, a plurality of bearings therefor, a driving connection on one side of one bearing leading to said wheels, and a driving connection for said reel extending angularly from said shaft at a point on the other side of said latter bearing and between both of said bearings.

37. In a mining apparatus, a wheeled truck carrying a cable reel, truck driving mechanism therefor including a driven shaft, a plurality of bearings therefor, a driving connection on one side of one bearing leading to said wheels, and a driving connection for said reel extending angularly from said shaft at a point on the other side of said latter bearing and between both of said bearings, said reel connection being adapted to be continuously driven while said truck is stationary.

38. In a mining apparatus, a wheeled truck carrying a cable reel, truck driving mechanism therefor including a driven gear and clutch mechanism, and driving connections for said reel driven by said gear and angularly extending from said mechanism at a point between the opposite sides of said gear and clutch.

39. In a mining apparatus, a wheeled truck, and a tiltable machine receiving frame thereon having an open rear end and a feed member receiving notch in the latter.

40. In a mining apparatus, a wheeled truck, a tiltable machine receiving frame thereon having an open rear end and a feed member receiving notch in the latter, and a feed member abutment carried on said truck in rear of said frame.

41. In a mining apparatus, a wheeled truck, a machine receiving frame thereon swiveled on a vertical axis and tiltable about a transverse pivot, said frame having an open rear end and a feed member notch therein, and a feed member abutment carried on the rear end of said truck.

42. In a mining apparatus, a wheeled truck, and a horizontally movable swiveled machine receiving frame thereon having an

open rear end and a feed member receiving notch therein and carrying an upstanding lateral abutment at one side of the said notch.

43. In a mining apparatus, a wheeled truck, and a horizontally movable swiveled machine receiving frame thereon having an open rear end and a feed member receiving notch therein and carrying upstanding lateral abutments at opposite sides of said notch.

44. In a mining apparatus, a wheeled truck, a vertically tilttable machine receiving frame thereon having a cross piece at the rear end thereof, and a plurality of anchoring means for a flexible feed member carried on said cross piece and so spaced that a flexible member leading from any one of a plurality of directions from said machine will apply a feeding force thereto substantially parallel to the longitudinal axis of said frame.

45. In a mining apparatus, a wheeled truck, a horizontally movable tilttable machine receiving frame thereon vertically tilted about an axis having a fixed relation with respect to a given point in said truck having a plurality of laterally spaced feed member receiving means on its rear end, and a feed member receiving means on the rear end of said truck.

46. In a mining apparatus a wheeled truck, a vertically tilttable machine receiving frame thereon, and a machine guiding frame movable longitudinally of said last mentioned frame and longitudinally separable therefrom.

47. In a mining apparatus, a wheeled truck, a vertically tilttable machine receiving frame thereon, a machine guiding frame movable longitudinally thereof and longitudinally separable therefrom, and mining machine mechanism movable with said guiding frame and longitudinally separable therefrom.

48. In a mining apparatus, a wheeled truck, a vertically tilttable machine receiving frame thereon, and a machine guiding frame movable longitudinally of said last mentioned frame in either the tilted or horizontal positions thereof and separable therefrom by a longitudinal movement when said receiving frame is in tilted position.

49. In a mining apparatus, a wheeled truck, a tiltable machine receiving frame pivoted on the front end thereof and having its front end engageable with the mine bottom, and a machine guiding frame adapted slidably to receive a mining machine on the mine bottom supported between the bottom and the front end of said frame and movable into operative position thereon with a mining machine.

50. In a mining apparatus, a wheeled truck, a rigid machine receiving frame tilted

able thereon, a cooperating guiding frame movable longitudinally of said frame and adapted to receive a mining machine moving on the mine bottom, a mining machine, 5 and latch mechanism between said mining machine and said guiding frame.

51. In a mining apparatus, a wheeled truck, a rigid machine receiving frame tilt-able thereon, a cooperating guiding frame 10 movable longitudinally of said frame and adapted to receive a mining machine moving on the mine bottom, and latch mechanism between said mining machine and said guiding frame including an element on said 15 mining machine and a plurality of cooper-ating elements on said guiding frame.

52. In a mining apparatus, a wheeled truck, a truck wheel driving shaft thereon, a lubricant containing casing, mechanism for 20 driving said shaft from a mining machine on the truck including a rotatable member in said casing, a clutch outside of said casing, and reel mechanism driven by said member when the truck is at rest.

25 53. In a mining apparatus, a wheeled truck adapted to support a separately oper-able machine of the type which is slidable on the mine bottom during cutting, a truck wheel driving shaft thereon, a lubricant con-30 taining casing, mechanism for driving said shaft from a mining machine on the truck including a rotatable member in said casing arranged coaxially with said shaft, and a clutch located outside of said casing for 35 directly connecting said member and shaft.

54. In a mining apparatus, a wheeled truck, an upright shaft adapted to be driven by a mining machine, a truck wheel driving transverse shaft, operative connections be-40 tween said shafts including a clutch having an element rotatable by the upright shaft when the truck is stationary, and a cable reel carried on said truck and rotatable with said element.

45 55. In a mining apparatus, a friction clutch, operating means therefor, and sup-plemental means to prevent maximum load-ing of said clutch always automatically op-erative when said clutch is once rendered in-50 operative.

56. In a mining apparatus, a clutch, oper-ating means therefor, and supplemental gravity operated means for controlling opera-tion of said clutch.

55 57. In a mining apparatus, a clutch, op-erating means therefor, supplemental gravity operated means for controlling operation of said clutch, and manually controlled means for releasing said means to allow said 60 clutch to be loaded.

58. In a mining apparatus, a wheeled truck, a shaft thereon adapted to be rotat-ed by a mining machine on said truck, truck wheel driving mechanism connectible 65 to said shaft and including a friction

clutch, operating means for the latter, and supplemental means for inhibiting uninten-tional maximum loading of said clutch.

59. In a mining apparatus, a wheeled truck, a transverse shaft thereon adapted to 70 be rotated by a mining machine on said truck, truck wheel mechanism connected to said shaft including a friction clutch, and means including a clutch operating lever and a cooperating lever normally engage-75 able with a part of said truck for inhibiting unintentional maximum loading of said clutch.

60. In a mining apparatus, a wheeled truck, truck wheel driving mechanism 80 thereon adapted to be driven by a mining machine on said truck and including a friction clutch, and operating means for the lat-ter including a pivoted member normally 85 extending transversely of said truck and a cooperating toggle means connected thereto and to the movable element of said clutch.

61. In a mining apparatus, a wheeled truck, truck wheel driving mechanism there-on adapted to be driven by a mining ma-chine on said truck and including a friction clutch, and operating means for the latter including a pivoted member and a co-operating toggle means connected thereto and to the movable element of said clutch, 90 said member normally extending transverse-ly of said truck.

62. In a mining apparatus, a wheeled truck adapted to support for transport a mining machine of the type normally adapt-ed to cut on its bottom on the mine bot-tom, truck wheel driving mechanism thereon adapted to be driven by a mining machine on said truck and including a friction clutch, and operating means for the lat-ter including a member pivoted to the truck and movable in an upright plane transversely of said truck and a member op-eratively connected to the movable element of said clutch and pivotally connected to said 100 first mentioned member.

63. In a mining apparatus, a wheeled truck adapted to support for transport a mining machine of the type normally adapt-ed to cut on its bottom on the mine 115 bottom, truck wheel driving mechanism thereon adapted to be driven by a mining machine on said truck and including a friction clutch, and operating means for the lat-ter including a member pivoted to the truck 120 and movable in an upright plane, a mem-ber laterally spaced therefrom pivoted to said truck and operatively connected to the movable element of said clutch, and a mem-ber pivotally connecting said members and 125 extending across said clutch.

64. In a mining apparatus, a wheeled truck, a transverse truck driving shaft thereon, a sleeve on said shaft adapted to be 130 driven by a mining machine on said truck, a

clutch element fixed to said sleeve and rotatable therewith without truck movement, a cooperating clutch member connected to said shaft, an operating member therefor, and toggle connected mechanism for actuating said member.

65. In a mining apparatus, a wheeled truck frame, an upright worm shaft thereon, a truck driving shaft thereon, a worm gear driven by said worm and rotatable on said shaft, a lubricant containing housing surrounding said gearing, a clutch element outside said housing rotatable on said shaft and constantly connected to one of the elements 10 in said housing, a cooperating clutch element fixed to said shaft and disposed coaxially therewith, and means for connecting said clutch elements.

66. In a mining apparatus, a wheeled truck, a horizontally swinging vertically tiltable machine receiving frame thereon, a machine guiding frame movable longitudinally of said last mentioned frame, means operatively connected between said truck and receiving frame for inhibiting lateral swinging of the latter, and means operatively connected 25 between said guide frame and truck for inhibiting tilting movement of said frames.

67. In combination, a wheeled truck, a horizontally swinging vertically tiltable machine receiving frame thereon, a machine guiding frame movable longitudinally of said last mentioned frame, means operatively connected 30 between said truck and receiving frame for inhibiting lateral swinging of the latter, means operatively connected between said guide frame and truck for inhibiting tilting movement of said frames, a mining machine on said guiding frame, and locking means for the latter operatively connected between said machine and truck.

68. In combination, a wheeled truck, a horizontally swinging vertically tiltable machine receiving frame thereon, a machine guiding frame movable longitudinally of said last mentioned frame, means operatively connected 45 between said truck and receiving frame for inhibiting lateral swinging thereof, means operatively connected between said 50 guide frame and truck for inhibiting tilting

movement of said frames, a mining machine on said guiding frame, locking means for said machine operatively connected between said machine and truck, and latching mechanism between said machine and said guiding frame.

69. In a mining apparatus, a wheeled truck carrying a cable reel and a transverse shaft, a flexible driving connection between 55 said shaft and reel, an idler pulley mechanism for said flexible member, and a hook adapted to engage said mechanism to hold the same in inoperative position.

70. In a mining apparatus, a wheeled truck, an element adapted to be movable thereon, and means for locking the same including a fixed element carried by said truck and having an inclined substantially flat surface and means cooperating therewith carried by said movable element and movable into vertically rigid locking relation with said fixed element when said movable element is in retracted position on said truck.

71. In a mining apparatus, a wheeled truck, a vertically tiltable mining machine receiving frame thereon adapted to slidably receive a mining machine of the type normally slidable on its bottom on the mine bottom during cutting, and means for locking 75 so said frame against tilting disposed at the rear and side of said truck and said frame when said frame is in locked position.

72. In a mining apparatus, a wheeled truck, a vertically tiltable frame thereon, and latch means disposed at the rear of said truck and having cooperating elements on said frame and truck to prevent tilting thereof.

73. In a mining apparatus, a truck, a member swiveled on the front end thereof on a vertical axis, roller mechanism between said member and truck disposed on opposite sides and in front and rear of said swivel, the front roller mechanism being at a greater distance from said swivel than the others, and a machine receiving frame tiltably mounted on said member on a horizontal axis adjacent the front edge thereof.

In testimony whereof I affix my signature.

MORRIS P. HOLMES.
